US0D1041457S

(12) **United States Design Patent** (10) **Patent No.:** **US D1,041,457 S**
(45) **Date of Patent:** **** Sep. 10, 2024**

(54) **PAIR OF EARPHONES**

(71) Applicant: **Shenzhen Shengling Technology Co., Ltd.**, Shenzhen (CN)

(72) Inventor: **Hua Lin**, Shenzhen (CN)

(**) Term: **15 Years**

(21) Appl. No.: **29/944,180**

(22) Filed: **May 27, 2024**

(30) **Foreign Application Priority Data**

May 8, 2024 (CN) 202430265780.7

(51) LOC (14) Cl. **14-01**

(52) U.S. Cl.

USPC **D14/223**

(58) **Field of Classification Search**

USPC ... D14/205, 207, 209, 209.1, 217, 221, 223, D14/225; D24/106, 173, 174 CPC . H04R 1/08; H04R 1/10; H04R 1/105; H04R 1/1016; H04R 1/1033; H04R 1/1066; H04R 5/033; H04R 5/0335; H04R 25/00

(57) **CLAIM**

The ornamental design for a pair of earphones, as shown and described.

DESCRIPTION

FIG. 1 is a perspective view of a pair of earphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the pair of earphones where the earphones are received in the charging case.

The dash-dash broken lines in the drawings depict portions of the pair of earphones that form no part of the claimed design.

1 Claim, 9 Drawing Sheets
